UNITED STATES PATENT OFFICE.

JOHN HOLMES, OF ST. CLAIR, PENNSYLVANIA.

IMPROVEMENT IN MINERS' SQUIBS.

Specification forming part of Letters Patent No. 121,783; dated December 12, 1871.

To all whom it may concern:

Be it known that I, JOHN HOLMES, of St. Clair, in the county of Schuylkill and State of Pennsylvania, have invented a new and useful Improvement in Miners' Squibs; and I do hereby declare that the following is a full, clear, and exact description thereof, which will enable others skilled in the art to make and use the same, reference being had to the accompanying drawing forming a part of this specification.

This invention relates to a new and useful improvement in squibs for the use of miners in the process of blasting coal, rock, &c.; and it consists in the construction and arrangement of parts hereinafter described.

In the accompanying drawing, Figure 1 represents the form of the paper for making the tube. Fig. 2 is a view of a squib partly in section. Fig. 3 is a longitudinal section of a squib constructed according to my invention.

Similar letters of reference indicate corresponding parts.

A is the squib; A', the paper, cut as seen in Fig. 1, with one end saturated with a solution of saltpeter, and dried, and then the beveled side is covered with mucilage or paste, so that when the paper is rolled into a tube, as seen in the drawing, the edge will adhere. The paper A' is rolled around a tapering piece of iron or other material of suitable size and form. C represents the powder with which the tube is filled. D is the match, which is properly prepared, and may

be rolled in the end of the tube, as seen in the drawing, or attached to the end of the tube in any other suitable manner. The powder is prevented from escaping from the end of the tube by means of the stopper E of soap or other suitable material in the end, as seen. The squib may be dipped in liquid sulphur to render it more inflammable, if desired.

The squib is used for the purpose of throwing fire through the small opening left in a cartridge by the withdrawal of the tapering piece of iron, or the needle, after the cartridge has been tamped in the hole which has been drilled in the coal or rock, or through a tube called a "blasting-barrel" that is generally put into the hole with the cartridge and left in when the blast is discharged.

Squibs of some kind are used by all miners, ordinarily made upon the spot, and consequently very imperfectly prepared and with material unsuited to the purpose. My object is to furnish these squibs as perfect as they can be made of the most suitable materials, and have them ready for use in mining and other districts.

Having thus described my invention, I claim as new and desire to secure by Letters Patent—

As a new and improved article of manufacture the squib A, substantially as and for the purposes described.

JOHN HOLMES.
